UNITED STATES PATENT OFFICE.

MAUNSELL B. JACKSON, OF TORONTO, ONTARIO, CANADA.

ENGINE STARTER.

Application filed November 20, 1924. Serial No. 751,000.

This invention relates to engine starters adapted to start internal combustion engines, and more particularly to that type in which a starter pinion is axially moved into and out of mesh with a gear on the engine, and my object is to provide a simple device of this character which will be of few parts that may be cheaply manufactured and yet be durable and efficient.

10 I attain my object by means of the constructions hereinafter described and illustrated in the accompanying drawings in which—

Fig. 1 is a side elevation of my device in its operative position;

15 Fig. 2 a similar view in its operative position;

Fig. 3 a cross section on the line 3—3 in Fig. 1;

20 Fig. 4 a side elevation of a modified form of the device showing it in its operative position; and

Fig. 5 an end view of the same.

25 In the drawing like reference numerals indicate corresponding parts in the different figures.

An electric motor 1 (only partly shown) is provided with an extended armature shaft 2 having an end 3 of reduced diameter. On 30 this end is secured, in any suitable manner, a collar 4 of substantially the same diameter as the main portion of the shaft 2. A pair of pins 5 and 5^a are carried at opposite sides of the collar and these pins are so positioned 35 relative to one another that they will engage the convolutions of a helical spring 6 freely disposed on the shaft and collar.

One end of the spring is bent laterally to 40 form a shoulder or a hook 7 which is normally free of or unconnected with the shaft or collar but is adapted to engage the pin 5 to form a rotary drive connection between the shaft and the spring. The other end of the spring is also bent to form a lateral projection 8 to which is connected a starter pinion 9. The pinion is loosely or freely carried on the shaft 2 and the connection between the projection 8 and the pinion is formed by passing the projection into a 45 notch or opening 10 formed in the pinion. To retain the projection in engagement with the pinion I secure, in any suitable manner,

a disk 11 to the latter. This disk is provided with a finger 12 which is suitably shaped to engage the end convolution of the 55 spring behind the projection 8. Preferably the disk will be a sheet metal stamping having sufficient material to form the finger formed on its periphery.

The pinion is adapted to mesh with a gear 60 13 connected with the crankshaft of an engine (not shown) the common practice being to secure the gear to the engine flywheel. The entering ends of the teeth of the pinion are also tapered off as shown to facilitate 65 the meshing of these teeth with the teeth of the flywheel gear.

Assuming the starter mechanism is in its normal position as shown in Fig. 1 and it is desired to start the engine, the mode of 70 operation is as follows. The motor 1 is energized which causes the shaft 2 and thus the collar 4 and the pins 5 and 5^a to rotate. As hereinbefore mentioned the spring 6 and the pinion 9 are freely carried on the shaft 75 2 and the inertia of the former parts permits the shaft to rotate relative to them. The pins meshing with the convolutions of the spring, axially feed or move the latter and the pinion towards the gear. When the 80 pinion has been axially moved a sufficient distance to fully mesh it with the gear, the hook 7 is adapted to engage the pin 5, to form a resilient rotary drive connection between the starter motor and the pinion 85 (see Fig. 2) which causes the crankshaft of the engine to be revolved. Should the ends of the pinion teeth happen to engage the ends of the teeth on the gear when they are being meshed the axial movement of the 90 spring 6 would be temporarily stopped and the pins 5 and 5^a would slightly compress the spring and thus partially rotate the pinion to mesh it with the gear. It will be noted that the use of two pins will prevent 95 distortion of the spring if the teeth on the pinion and gear jam as just described. Immediately the pinion meshes with the gear the latter prevents any tendency of the spring to rotate with the shaft until the 100 hook 7 engages the pin 5. To ensure this engagement between the hook and the pin, a shoulder 15 is provided for engaging the pinion to limit its inward movement. The

shoulder may be formed on the shaft 2 or a bearing for the latter may be utilized to engage the pinion when it is in mesh with the gear.

5 The pinion is returned to its inoperative position, when the engine is started, in the following manner. The pins 5 and 5^a are axially spaced, on the collar 4, a distance equal to one-half the normal pitch of the 10 convolutions of the helical spring 6, the pin 5 being located closer to the outer end of the shaft. The speed of the flywheel gear when operated by the starter motor is less than its speed when the engine is started 15 so that the instant the engine starts, the speed of the starter pinion, relative to the starter shaft, is increased. This causes the hook 7 to be disengaged from the pin 5 and the convolutions of the spring to be 20 threaded on the pins to move the pinion out of mesh with the gear. An abutment 14 formed on or secured to the collar 4 is adapted to engage the hook 7 to limit its outward movement.

25 In the modified construction of my device as shown in Fig. 4 the collar 4 is omitted and the free end of the shaft is provided with a pin 14^a to form an abutment to limit the outer movement of the 30 hook 7. In this construction only one pin 5 is used for threading the spring which will work satisfactorily to mesh the pinion with the gear. When only one pin is used it is necessary to provide sufficient compression in the spring to cause it to tend to 35 thread itself on the pin. This is accomplished by locating the shoulder 15 relative to the pin 5 so that it is adapted to engage the adjacent side of the pinion 9 before 40 the pin 5 engages the hook 7 so that the spring 6 will be slightly compressed before the rotary drive connection is formed. From this it follows that when the hook 7 is disengaged from the pin 5, due to the 45 engine being started as hereinbefore described, the end convolution of the spring, on which the hook is formed, will bear against the pin and ride past it to engage the outer side of the pin. The pin is then 50 positioned between the convolutions of the spring and the rotary movement of the latter will cause it to be threaded on the pin to move the pinion out of mesh with the gear.

55 The convolutions of the spring are preferably rectangular in cross section to provide a maximum line of contact with the pin.

Whether the shaft 2 and collar 4, shown in 60 Figs. 1 and 2, or the shaft 2, as shown in Fig. 4, be used, a substantially smooth and unbroken surface will be provided for the spring 6 to grip, which surface will not tend to distort the latter. As the pinion 9 is 65 mounted directly on the shaft 2 it is pos-

sible to attain a low gear ratio between the pinion and the gear and at the same time have a shaft of ample cross section without using double reduction gearing to obtain these features.

The hereinbefore described arrangement and construction of the parts permits a short spring 6 to be used which tends to lessen the severity of a sudden shock due to a back fire of the engine when starting the 75 latter.

It is to be distinctly understood that the word "hook" in the specification and claims means any type of projection or shoulder formed on or secured to the spring 6 80 for forming a driving connection between the spring and the starter shaft whereby the former will be positively rotated by the latter. The word "pin" in the specification and claims means a projection or lug formed 85 on or carried by the shaft.

What I claim is:—

1. The combination with an internal combustion engine provided with a gear for revolving the crank shaft thereof, of starter 90 mechanism including a shaft; a pinion freely carried on the shaft and normally out of mesh with the gear; a helical spring freely mounted on the shaft and having one end connected with the pinion and the other 95 end provided with a hook normally unconnected with the shaft; a pin carried by the shaft for forming a threading engagement between the latter and the spring whereby the pinion will be axially moved in opposite 100 directions by the rotation of the shaft or the pinion relative to one another, the pin being also adapted to engage the hook to form a rotary drive connection between the shaft and the pinion; and an abutment supported 105 in the path of the pinion for engagement by the pinion to limit its axial movement in its gear meshing position, the pinion being adapted to engage the abutment before the pin engages the hook whereby the pin causes 110 the spring to be compressed to assist its return movement.

2. The combination with an internal combustion engine provided with a gear for revolving the crank shaft thereof, of starter 115 mechanism including a shaft; a pinion freely carried on the shaft and normally out of mesh with the gear; a helical spring freely mounted on the shaft and having one end connected with the pinion and the other 120 end provided with a hook normally unconnected with the shaft; a pin carried by the shaft for forming a threading engagement between the latter and the spring whereby the pinion will be axially moved in opposite 125 directions by the rotation of the shaft or the pinion relative to one another, the pin being also adapted to engage the hook to form a rotary drive connection between the shaft and the pinion; an abutment supported 130

in the path of the pinion for engagement by the pinion to limit its axial movement in its gear meshing position, the pinion being adapted to engage the shoulder before
5 the pin engages the hook whereby the pin causes the spring to be compressed; and an abutment carried by the end of the shaft remote from the first mentioned abutment, the second mentioned abutment being adapted to engage the hook to limit the movement 10 of the pinion in its unmeshed position.

Signed at Toronto, Canada, this 15th day of November, 1924.

MAUNSELL B. JACKSON.
